UNITED STATES PATENT OFFICE.

THOMAS D. LOCKWOOD, OF MALDEN, AND THOMAS W. LANE, OF BOSTON,
MASSACHUSETTS.

MAGNETO-ELECTRIC TELEPHONE.

SPECIFICATION forming part of Letters Patent No. 292,335, dated January 22, 1884.

Application filed July 28, 1883. (No model.)

To all whom it may concern:

Be it known that we, THOMAS D. LOCKWOOD, of Malden, in the county of Middlesex and State of Massachusetts, and THOMAS W. LANE, of Boston, county of Suffolk, and State of Massachusetts, have invented a new and useful Improvement in Magneto-Electric Telephones, which improvement is fully set forth in following specification.

- 10 This invention has reference to that class of articulating - telephones commonly employed as receivers, but capable of use as transmitters as well, which comprise a vibratory magnetic diaphragm, or vibratory diaphragm and 15 armature, and a permanent magnet, with a spool or bobbin of insulated wire on one or both poles; and it consists in the combination, with the permanent magnet of such an instrument, of an additional spool or bobbin, 20 which may be included in circuit with an electric battery for intensifying and maintaining the magnetism, said additional spool or bobbin being placed on the same pole with the usual spool or bobbin of the telephone.
- 25 It also consists in the arrangement of said two spools or bobbins on the same soft-iron pole-piece or pole-pieces, and in close proximity to each other, the re-enforcing bobbin or spool being preferably on the inside between 30 the ordinary spool, (which is included in the telephone-circuit or line-wire,) the object being to make the instrument as small and compact as may be (the pole-pieces being smaller than the body of the weight) and as effective.
- 35 It further comprises the combination, with the instrument having the two bobbins, spools, or coils, and the battery-circuit including one of said bobbins, spools, or coils, of a switch for breaking the said circuit when the instrument is not in use; and, also, the combination and arrangement of circuits and switch whereby the battery commonly used with the transmitter is made available also to re-enforce, intensify, or maintain the magnetism of the receiver.

In the accompanying drawings, Figure 1 is a section of a telephone constructed in accordance with the invention and employing a horseshoe-magnet; Fig. 2, a bottom view of the same; Fig. 3, a diagram of the circuit-connections when the instrument is in use; Fig.

4, a similar diagram, showing an instrument with a bar-magnet; Fig. 5, a side view, partly in section, of a hand-telephone constructed in accordance with the invention; Fig. 6, a diagram showing a switch for breaking the battery-circuit when the instrument is not in use; Fig. 7, a diagram illustrating a portion of a switch-board, with a connector and circuits adopted for use with the improved instrument; and Fig. 8, a diagram of the connections when the transmitting-battery is utilized.

A is the mouth or ear piece; B, the inclosing-case; C, Figs. 1 and 2, a bracket; D, the vibratory diaphragm of magnetic material—such as soft iron; and M, the permanent magnet, preferably of steel. Referring to Fig. 1, the magnet M is bent so that there are at the ends projections *d d'*. In these projections the inner ends of the soft-iron pole-pieces *c c'* are fixed. The re-enforcing bobbins, spools, or coils *b b'* are placed on the pole-pieces at the inner end thereof. The other or ordinary bobbins, *a a'*, are placed on the same pole-pieces at the outer end. The pole-pieces or cores of the bobbins are bent so that the ends of the bobbins *a a'* face the diaphragm D, while the bobbins *b b'* present their sides to it.

The bracket C on the back of the instrument is for fastening it to an arm or rod, which passes through the core *e*, the set-screw *f* retaining the instrument in place and permitting it to be adjusted when desired.

The bobbins or re-enforcing coils *b b'* are included in the circuit of an electric generator or galvanic battery, *k*, and the connections are so made that the electro-magnetism created by the galvanic current increases and maintains the magnetism of the magnet. The bobbins *a a'* are connected to line in any ordinary way. The binding-posts forming connections with the exterior conductors are lettered *g h i j* in Fig. 2.

Although the circuit of battery *k* may be constantly closed, practically this would involve a waste of electric energy, and therefore switches for breaking the battery-circuit would be employed. The arrangement of these is described below.

In Figs. 4, 5, 6, the bar-magnet M has only one pole-piece, *c*, which forms a core to both

bobbins, spools, or coils *a* and *b*. As before, the re-enforcing bobbin *b* is nearest the magnet; the bobbin *a* nearest the diaphragm D.

1, 2, 3, and 4, Figs. 4 and 5, are the binding-posts. The battery *k* is included in a loop between the posts 2 and 3. In Fig. 6 there are only three binding-posts, 1, 2, and 3, the post 3 being connected by the wire *m* with the bobbin or coil *b*, and by the wire *l* with the bobbin *a*. The post 2 is connected by wire *m'* with the other terminal of the coil or bobbin *b*; the post 1 by the wire *l'* with the like terminal of the bobbin *a*. In this figure the circuit of the battery *k* is broken, and the two terminals are connected with the contact-plates 5 and 6, respectively, which are insulated from each other. The switch-lever *p* of the ordinary gravity-switch connects together the two plates when relieved of the weight of the telephone, so that the circuit of the battery *k* through the bobbin or coil *b* is complete only when the telephone is in use. When the transmitter-battery is used to increase and maintain the magnetism of the receiver, the connections are as shown in Fig. 8. The circuit of the battery *k* includes the contact-plates 5 6, binding-post 3, re-enforcing bobbin or coil *b*, binding-post 2, primary of induction-coil 9, and transmitter 10. The telephone-circuit or main line is divided, one branch passing from the contact-plate 6, binding-post 3, principal bobbin or coil of the telephone-receiver *a*, binding-post 1, and secondary of induction-coil to line or ground; the other from the contact 7, 35 through signal-bell 8, to line out or ground.

When the telephone is suspended from the switch-lever *p*, as shown, the circuit of battery *k* is broken, and the signal-bell 8 only is in circuit. When the telephone is removed, the battery-circuit is closed by the switch *p* between the contact-plates 5 and 6, and the main line is completed through the telephone-receiver and the secondary of the induction-coil.

For use at the central office or at other points a plug, *P*, is provided. This plug is divided into four parts, which, as they are connected, respectively, with the binding-posts 1, 2, 3, and 4, are correspondingly marked 1', 2', 3', 4'. For convenience of illustration the plug is shown partly in cross-section. The plug is inserted in the opening between the plates 12 and 13, 14 and 15, so that the posts 1 and 4 are connected with the plates 12 and 13, respectively, and the bobbin *a* (of Figs. 4, 5, and 6) or bobbins *a* *a'* (of Figs. 1 and 3) are included in the line-circuit, while the posts 2 and 3 are connected with the plates 14 and 15, respectively, and are thus included in the local circuit or battery *k*. It is obvious that a number of lines may center in a switch-board provided with a set of plates—such as 12, 13, 14, and 15—for each line-circuit; also, that a single battery may be connected with several pairs of plates, 14 and 15.

65 The details of construction may be greatly modified without departing from the spirit of

the invention, and portions of the invention may be used separately. For example, the particular switches shown need not be employed; but other known and suitable systems may be adopted to use with the improved instrument.

Although it is preferred to have the two bobbins or two sets of bobbins on the same end or ends of the magnets and on pole-pieces smaller than the body of said magnets, and although this construction is specially claimed, yet it is obvious that one or more bobbins placed at other parts of the magnet could be used to intensify and maintain the magnetism thereof.

We claim—

1. The combination, with a telephone comprising a permanent magnet and two coils or bobbins placed on the same pole of the magnet, of a battery included in circuit with one of said coils or bobbins, so as to increase the magnetism of said magnet, the other coil or bobbin being included in the telephone circuit or line, substantially as described. 85

2. The telephone having the two coils or bobbins, or two sets of coils or bobbins, placed on the same pole-piece or pole-pieces of the permanent magnet, in combination with an exciting-circuit including a battery and one coil or bobbin, or one set of coils or bobbins, so that the current intensifies and maintains the magnetism of the magnet, and the telephone circuit or line including the other coil or set of coils, substantially as described. 95

3. A telephone comprising, in combination with the diaphragm, permanent magnet with one or more pole-pieces, and a bobbin at the end of each pole-piece, a second bobbin placed on each pole-piece inside the first-named bobbin, between it and the end of the body of the magnet, substantially as described. 105

4. The combination, with a telephone having a magnet and two bobbins or coils, one included in circuit with a battery, so as to intensify and maintain the magnetism, and the other in the telephone-circuit, of a key for opening said battery-circuit when the telephone is not in use, and closing it when the instrument is to be used, substantially as described. 110

5. The combination, with a transmitter and its battery, of a telephone comprising a magnet with two coils or sets of coils, one included in the circuit of said battery, and the other in the telephone-circuit, and a switch for opening the battery-circuit when the instruments are not in use, substantially as described. 120

In testimony whereof we have signed this specification in the presence of two subscribing witnesses. 125
